UNITED STATES PATENT OFFICE.

JOHAN M. ANDERSEN, OF BOSTON, MASSACHUSETTS, ASSIGNOR TO ALBERT AND J. M. ANDERSEN MANUFACTURING COMPANY, OF BOSTON, MASSACHUSETTS, A CORPORATION OF MAINE.

ELECTRICAL CONNECTION.

1,078,763.

Specification of Letters Patent.

Patented Nov. 18, 1913.

Application filed March 23, 1912. Serial No. 685,806.

To all whom it may concern:

Be it known that I, JOHAN M. ANDERSEN, a citizen of the United States, residing in Boston, county of Suffolk, and State of Massachusetts, have invented an Improvement in Electrical Connections, of which the following description, in connection with the accompanying drawings, is a specification, like letters on the drawings representing like parts.

This invention relates to an electrical connection comprising a socket member, and a plug member which is adapted to be inserted into and removed from the socket member.

The present invention has for its object to provide an electrical connection of the character described, which is especially adapted for use in circuits carrying currents of large amperage, such for instance as circuits employed for charging storage batteries, and particularly storage batteries on Pullman and other cars.

The plug member is designed to be located at a railway or other station, and the socket member is secured to the Pullman or other car, consequently a single plug member is used with a plurality of socket members, and is required to make proper contact with each socket member. Furthermore, the plug member is required to be handled by the operator whose duty it is to charge the battery and therefore should be made as light as possible, to enable it to be readily handled.

The contact members are required to be made of the proper size to carry the large current, and in order to prevent lateral movement of the contact members of the plug member with relation to the contact members of the socket member and also to relieve said contact members from strain, due to the weight of the plug, the latter and the socket member are provided with guiding members which are located centrally in said plug and socket members. The guiding members may and preferably also serve as means for securing the contact members firmly within the plug and socket members.

Provision is made for thoroughly insulating the contact members from the metal shells or casings and from each other within said shells or casings, as will be described. Provision is also made for quickly and easily assembling together the parts of the plug and socket members, as will be described.

These and other features of this invention will be pointed out in the claims at the end of this specification.

Figure 1 is a side elevation with parts broken away of the socket member of an electrical connection embodying this invention. Fig. 2, a side elevation of the plug member of the connection. Fig. 3, a vertical central section of the connection in its operative condition. Fig. 4, a horizontal section of the connection in its operative position. Fig. 5, a cross section on the line 5—5 Fig. 3. Fig. 6, a cross section on the line 6—6 Fig. 3. Fig. 7, a cross section on the line 7—7 Fig. 3. Figs. 8, 9 and 10, details of contact members to be referred to.

Referring to the drawings, *a* represents the plug member and *b* the socket member of an electrical connection embodying this invention. The plug member *a* comprises as herein shown, a metal casing 10 open at its front end and substantially closed at its rear end by a cap composed of two parts or halves 12, 13, which are detachably fastened to the casing 10 by screws 14. The casing 10 is provided within it with a transverse partition wall or cross bar 15, which has extended from it toward the rear end of the metal casing 10, a central hub 18 and side walls 19, 20, see Fig. 5, which sub-divide the rear portion 21 of the casing into two substantially parallel compartments 22, 23.

The side walls 19, 20, the hub 18, and the partition wall 15 may and preferably will be cast in one piece with the metal casing 10, and the rear portion 21 of the latter is substantially diamond shaped in cross section and materially larger than the cylindrical front portion of said casing as represented in Fig. 5. The bottom walls 24, 25 of the compartments 22, 23, are substantially in line with the partition wall 15 and are separated therefrom by spaces for a purpose as will be described.

The cylindrical front portion of the casing 10 is designed to contain the contact members of the plug member and forms a contact chamber 26 of said casing. The plug contact members are preferably made as herein shown and consist of two cylinders 27, 28 of copper or other metal and of different diameters, so that one cylinder as 28 may be nested in the other cylinder 27.

The cylinders 27, 28 are open at their front ends and provided at their rear ends

with heads 29, 30, having central openings 31, 32, see Figs. 8 and 9, for a purpose as will be described, and said cylinders have extended rearwardly from said heads terminal arms 33, 34, which are extended into the terminal compartments 23, 22, wherein they have secured to them by screws 35, 36, terminal blocks 37, 38, having sockets 39, 40 for the reception of the conductors or cables (not shown), as they may be of any suitable or well known construction.

The contact members 27, 28 are firmly secured within the metal casing 10, which is accomplished as herein shown by the guiding member of the plug, which is preferably made as herein shown and consists of a cylindrical rod 41 preferably of steel.

The rod 41 is provided with a flange 42 and beyond the latter with an enlarged rear portion, which extends through the hub 18 of the casing 10 and is provided at its end with screw threads, for the reception of a nut 44, by turning up which the plug guiding member may be moved longitudinally to secure the contact members of the plug member in fixed relation to the metal casing.

The plug contact members and the guiding member thereof, are thoroughly insulated from the metal casing 10, which is effected as follows: The guiding member 41 is insulated from the metal hub 18 by a bushing or sleeve 45 of insulating material, which extends into the chamber 26 of the casing 10, and insulates the guiding member from the heads of the contact members 27, 28. The flange 42 on the guiding member is insulated from the contact member 28 by a recessed washer 47 of insulating material, interposed between the said flange and the head 30 of the inner contact member 28. The contact member 28 is insulated from the contact member 27 by the recessed washer 48 of insulating material, interposed between the heads 29, 30 of the contact members 27, 28. The head 29 of the contact member 27 is insulated from the partition wall 15 by a washer 49 of insulating material.

The terminal arms 33, 34 of the contact members 27, 28 are insulated from the metal side walls 19, 20 by pieces 50, 51 of insulating material, see Figs. 4 and 5, and are insulated from the metal casing 10 by the pieces 52, 53 of insulating material, which bear against the rear walls 24, 25 of the compartments 22, 23 and extend toward the side walls 19, 20, but are separated therefrom by spaces through which the terminal arms 34, 33 are extended. These pieces 52, 53 also insulate the terminal blocks 38, 37 from the bottom walls 24, 25 of the compartments 22, 23, and the outer walls of said compartments are insulated from the said terminal blocks by bent pieces 55, 56 of insulating

material, which close the openings 57, 58 in said outer walls, through which access to the screws 36, 35 is had. The nut 44 and a metal washer 60 on the threaded end of the guiding member 41 are also insulated from the hub 18 by the washer 61 of insulating material.

By reference to Figs. 4 and 5, it will be seen, that the pieces 50, 51, 52, 53, 55, 56 of insulating material form a lining of insulating material for the walls of the compartments 22, 23, whereby the metal casing 10 is thoroughly insulated from the terminal arms and blocks of the contact members 27, 28, and the contact members are thoroughly insulated from each other and from the guiding member of the plug, by the insulating washers 47, 48 and bushing 45, and that the guiding member is insulated from the metal hub 18 by the bushing 45 and washer 61. As a result of thus thoroughly insulating the metal casing 10 from the metal parts within it, danger of serious accident and even death by the large current passing through the contact members is avoided. The contact members 27, 28 are preferably cylindrical in form, and in order that the smaller cylinder 28 may be nested within the larger cylinder 27, the head 29 of the latter is provided with an opening 65 for the passage of the terminal arm 34 on the smaller cylinder, said opening being located on the opposite side of the center from the terminal arm 33, see Fig. 4. The cylinders 27, 28 of the contact members are provided with longitudinally extended slits 66, 67 for a purpose as will be described. The guiding member of the plug is made substantially long and projects beyond the front end of the metal casing 10, for a purpose as will be described. The socket member is of substantially the same construction as the plug member and comprises a short metal cylinder 70 provided with an enlarged rear portion 71, which has within it a transverse partition wall 72, a metal hub 73 extended rearwardly therefrom, and side walls integral with the hub and forming within the enlarged portion 71 of the casing, compartments 76, 77, for the reception of the terminal blocks 78, 79, and arms 80, 81 extended from the heads 82, 83 of the cylindrical contact members 84, 85. The contact members 84, 85 are secured in fixed relation to the casing 70, by a female guiding member, which consists of a rod 90, preferably of steel, and provided with a socket 91 for the reception of the male guiding member 41. The rod 90 is provided between its ends with a flange or collar 92, and has its rear end extended through the central hub 73 and is provided at its rear end with screw threads, which are engaged by a nut 93, which co-operates with the hub 73 to firmly secure the con-

tact members 84, 85 in fixed relation to the metal casing 70. The contact member 84 is nested within the contact member 85, and has its terminal arm 80 extended through an opening 95 in the head 83 of the contact member 85, and also through an opening in the head 96 of a cylinder 97 of insulating material, which is interposed between the contact cylinders 84, 85. The contact cylinder 85 is insulated from the metal casing 70 by a recessed disk 197 of insulating material, into which the contact cylinder 85 is inserted. The disk 197 is provided with openings through which the terminal arms 80, 81 of the contact members 84, 85 are passed into the compartments 76, 77. The female guiding member 90 is insulated from the hub 73 by a bushing or sleeve 98 of insulating material, and the terminal arms 80, 81 and blocks 78, 79 within the compartments 76, 77 are insulated from the walls thereof, by the substantially flat pieces 100, 101 and by the bent or curved pieces 102, 103 of insulating material, which are capable of being inserted into the compartments 76, 77 through the open end of the same. The female guiding member has loose on it a metal washer 104 against which the nut 93 bears, and a washer 105 of insulating material is interposed between the metal washer 104 and the hub 73.

By reference to Figs. 3 and 4, it will thus be seen, that the contact members 84, 85 are insulated from each other by the cylinder 97 of insulating material, and from the metal casing by the insulating disk 197, and that the female guiding member 90 is insulated from the metal casing by the bushing 98 and washer 105, and that the terminal arms 80, 81 and blocks 78, 79 are insulated from the metal casing by the flat pieces 100, 101, curved pieces 102, 103, and by flat pieces 108, 109 interposed between the said terminal blocks and the end walls 110, 112 of the compartments 76, 77. The cylinders of the contact members 84, 85 are provided with longitudinally extended slits 167, 168 to form spring fingers, and the cylinders of the plug contact members are made to enter the cylinders of the socket contact members, and in order to obtain a superior contact between said cylinders, the cylinders of the plug contact members are of an external diameter slightly larger than the internal diameter of the cylinders of the socket member as represented in Fig. 10. By reason of the fact that the contact cylinders of the plug and socket members are split longitudinally and capable of yielding, the cylinders of the plug member are capable of yielding inwardly or contracting, while the cylinders of the socket member are capable of yielding outwardly or enlarging, and as a result the said cylinders when forced together are converted into tapering cylinders, with the

cylinders of the plug member tapering inwardly and the cylinders of the socket member tapering outwardly, so that the cooperating cylinders make contact for their entire length, whereby a very superior electrical connection between the contact members of the plug and socket members is obtained.

Provision is made for securing the socket member to the railway car, so that it is firmly secured against working loose but yet is capable of turning, so that in case the car should be suddenly started while the battery thereon is being charged, the socket member will be turned into the line of stress and will automatically disengage itself from the plug member, thereby avoiding injury to both members. For this purpose, the casing of the socket member is provided with a laterally extended projection 120 from which extends an annular flange 121, which cooperates with the bottom 122 of a hollow casting 123, into which the projection 120 extends through a hole in the bottom 122. The casting 123 is provided with ears 124, having holes for the passage of bolts 125, by which the casting is secured to the bottom of the railway car represented by the line 126 in Fig. 3. The socket member is pivotally secured to the casting 123 or supporting member by a convexed steel disk or washer 127, fitted over the projection 120 and bearing at its outer circumference against the bottom 122 of the casting and at its inner circumference against the under side of a cap plate or disk 128, which is detachably secured to the projection 120 by bolts 129. The spring washer 127 serves as a support on which the socket member swivels and also as a spring to keep the flange 121 in close contact with the bottom of the casting 123 to prevent rattle. The socket member is also provided with a cylindrical cover 130, which is pivoted to the casting 70 and is designed to fit over the contact members thereof and protect the same from injury, when the plug member is withdrawn.

By providing the plug and socket members with center guiding members, the latter are not only capable of being used to secure the contact members in fixed position within their casings, but the contact members are enabled to be made short in length and of substantially large diameter and split longitudinally to render them capable of yielding so as to convert the normally cylindrical contact members into tapering contact members when in engagement, whereby contact for the length of the normally cylindrical contact members is obtained and a superior contact obtained. Furthermore, the contact members of the socket member may project beyond the casing of the said member, without danger of said

contact members being sprung out of shape or distorted by the weight of the plug member and of the heavy cable attached thereto, because the center guiding members are in firm engagement before the contact members are brought into contact, and as a result, springing of the contact members of the socket member by the weight of the plug member and its attached cable is avoided.

I have herein shown one construction of electrical connection embodying this invention, but it is not desired to limit the invention to the particular construction shown.

In the present instance the invention is shown in a double pole device in which the contact members 27, 85 are of one polarity and the contact members 28, 84 are of the other polarity, but it is not desired to limit the invention in this respect, as the guiding members may be used to advantage with a single pole device. In the present instance, the male guiding member 41 forms part of the plug member and projects beyond the contact member thereof, but if desired, the male and female guiding members may be reversed, and further the female member may be the longer member and project beyond the contact member with which it is associated. It will be observed, that the projecting guiding member is dead, that is, it is thoroughly insulated from the contact member or members with which it is associated, whereas the other guiding member which does not project need not be insulated from the contact member with which it is associated.

Claims.

1. In an electrical connection of the class described, in combination, a socket member provided with a metal casing having cylindrical contact members nested one within the other and separated from each other, means for insulating said members from each other and from said casing, a female guiding member located within the nested contact members, and a plug member provided with a metal casing having cylindrical contact members nested one within the other, and separated from each other, means for insulating said plug contact members from each other and from said casing, and a male guiding member located within the nested contact members of said plug member and coöperating with the female guiding member of said socket member, substantially as described.

2. In an electrical connection of the class described, in combination, a socket member provided with a metal casing having cylindrical contact members slotted longitudinally and nested one within the other, and separated from each other, a guiding member located within the nested contact members, and a plug member provided with a

metal casing having cylindrical contact members split longitudinally and nested one within the other, the cylindrical contact members of said plug member having external diameters slightly larger than the internal diameters of the cylindrical contact members of said socket member, means for insulating the contact members of said plug member from each other and from the metal casing of said plug member, and a guiding member located within the cylindrical contact members of said plug member and coöperating with the guiding member of said socket member, substantially as described.

3. In an electrical connection of the class described, in combination, a socket member provided with a substantially cylindrical contact member, and with a substantially central guiding member located within said contact member, and a plug member provided with a substantially cylindrical contact member, and with a substantially central guiding member located within the contact member thereof to engage the guiding member of the socket member, one of said guiding members being extended beyond the contact member within which it is located to engage the coöperating guiding member before the contact members of the plug and socket members are engaged with each other, substantially as described.

4. In an electrical connection of the class described, in combination, a socket member provided with a plurality of contact members nested one within the other and insulated from each other, and with a substantially central guiding member located within said nested contact members, and a plug member provided with a plurality of contact members nested one within the other and insulated from each other and coöperating with the contact members of the socket member, and having a substantially central guiding member located within the nested contact members thereof and coöperating with the guiding member of the socket member, substantially as described.

5. In an electrical connection of the class described, in combination, a metal casing provided with a partition wall having a hub extended from it, cylindrical contact members having heads from which extend terminal arms, said contact members being nested together, with the terminal arm of the inner contact member extended through an opening in the outer contact member, means for insulating said contact members from each other and from said casing, and a guiding member extended through said contact members and through said hub, and means to secure said guiding member to said casing, substantially as described.

6. In an electrical connection of the class described, in combination, a metal casing provided within it with a hub, a guiding

70

member supported at one end by said hub, means to secure said guiding member in said hub, a contact member within said casing, means coöperating with said guiding member for securing said contact member in said casing, and means for insulating said contact member from said casing, substantially as described.

7. In an electrical connection of the class described, in combination, a contact member provided with a head having in it a substantially central opening and a second opening at one side of its center and a terminal arm extended beyond said head, a second contact member provided with a head having a substantially central opening and having a terminal arm at one side of the center of said head and extended through the second opening in the head of the first mentioned contact member, and means to insulate said contact members, substantially as described.

8. In an electrical connection of the class described, in combination, a contact member provided with a cylindrical body portion split longitudinally and having a head provided with a substantially central opening and with a second opening at one side of said central opening, and having a terminal arm extended beyond said head, a second contact member provided with a cylindrical body portion of smaller diameter split longitudinally and nested within the first mentioned contact member, said second contact member having a terminal arm extended through the opening at one side of the center of the first mentioned member and having a head provided with a substantially central opening, a guiding member extended through the said central openings, and means to insulate said members, substantially as described.

9. In an electrical connection of the class described, in combination, a metal casing provided within its rear portion with means for forming substantially parallel compartments, contact members within the front portion of said casing having terminal arms extended into said compartments, means to secure said contact members in said casing, and means within said compartments to in-

sulate said terminal arms from said casing, substantially as described.

10. In an electrical connection of the class described, in combination, a metal casing provided within it with means for forming compartments and having openings in its outer wall for gaining access to said compartments, contact members within said casing having terminal arms extended into said compartments, means to secure said contact members in said casing, terminal blocks, means to secure said blocks to said terminal arms, said securing means being accessible through the openings in the outer wall of said casing, and means within said compartments to insulate the terminal blocks and arms from said casing, substantially as described.

11. In an electrical connection of the class described, in combination, a metal casing provided within it with means for forming compartments and having openings in its outer wall for gaining access to said compartments, contact members within said casing having terminal arms extended into said compartments, means to secure said contact members in said casing, terminal blocks, means to secure said blocks to said terminal arms, said securing means being accessible through the openings in the outer wall of said casing, and removable linings of insulating material for said compartments forming closures for said openings.

12. In an electrical connection of the class described, in combination, a metal casing provided within it with means for forming compartments, said metal casing having openings in the outer walls of said compartments, contact terminals in said compartments, and removable linings of insulation for said compartments forming closures for said openings, substantially as described.

In testimony whereof, I have signed my name to this specification in the presence of two subscribing witnesses.

JOHAN M. ANDERSEN.
